SMOKER'S APPLIANCE

Julius Schuelein, New York, N. Y.

Application December 28, 1945, Serial No. 637,530

1 Claim. (Cl. 131—171)

1

My invention relates to an appliance, and more particularly to a smoker's appliance.

For reasons of health, many people, who used to be heavy smokers, are forbidden to smoke in the customary way by inhaling and exhaling the fumes of tobacco, or due to some mouth or tongue irritation, they have to avoid to bring tobacco in any form, such as cigars or cigarettes, or even the mouth piece of cigar- or cigarette-holders in touch with mouth or tongue. In fact, it is common knowledge that it is extremely difficult for smokers to discontinue smoking, and in many instances the discontinuing of smoking causes great disturbances of psychological or other nature.

An object of my invention is to provide an appliance, which permits the user thereof to have the satisfaction of the aroma of a cigar, or cigarette, without inhaling the fumes of tobacco.

Another object of my invention is to provide an appliance, by means of which the user thereof may produce smoke from a cigar or cigarette, without inhaling the fumes of tobacco, so that he has the satisfaction of seeing and smelling smoke, which plays an important role to smokers.

A further object of my invention is to provide an appliance, by means of which nervous people, who were used to smoke more or less only for nervous reasons, obtain a perfect substitute for the customary smoking to steady their nerves.

Still another object of my invention is to provide an appliance, which permits the user thereof to have substantially the same satisfaction as if he would smoke by inhaling and exhaling fumes of tobacco, which, however, prevents the user from inadvertently bringing a cigar or cigarette to the mouth.

My invention consists in certain novel features of construction of my improvements as will be hereinafter fully described.

The above mentioned objects and advantages as well as other objects and advantages will be more fully disclosed in the following specification, reference being had to the accompanying drawing forming part of this specification, wherein:

Fig. 1 is a side elevational view of a smoker's appliance for cigars according to the invention,

Fig. 2 is an exploded view of the smoker's appliance shown in Fig. 1,

Fig. 3 illustrates a portion of the smoker's appliance shown in Fig. 1 in a different state of operation, and

Fig. 4 illustrates a holding member for cigarettes for use in a smoker's appliance according to the invention.

2

Referring now to Figs. 1-3, 10 generally indicates a rubber bulb for blowing air. Said rubber bulb has an air inlet opening 12 with a check valve 14 in its wall at one of its ends and has an outlet 16 at its other end. Said outlet 16 is shaped for receiving the end 18 of a hollow holding member generally indicated by 20. The other end 22 of said holding member 20 is shaped for receiving the end of a cigar 24. When the end 18 of the holding member 20 is inserted into the outlet 16 of the rubber bulb 10 as shown in Figs. 1 and 3, the outlet of the rubber bulb is connected with the interior of the holding member 20 and air may be blown through the channel 26 connecting the open ends 18 and 22 of the holding member 20 with each other into a cigar 24 inserted into the end 22 of the holding member 20. Said blowing of air may be obtained by alternating compressing (see Fig. 3) and releasing (see Fig. 1) the rubber bulb 10. During smoking when the bulb is released air will enter the bulb through inlet opening 12 and smoke and air will enter the bulb through the holding member 20. When the bulb is compressed air and an air and smoke mixture will pass out through the holding member 20.

According to the embodiment shown in Figs. 1-3, the end 18 of the holding member 20 is disengageably inserted into the outlet 16 of the rubber bulb. This feature facilitates the cleaning of the appliance and permits an easy replacement of the holding member 20 by another holding member of substantially the same shape or of a different shape.

For example, if after using the appliance for a cigar with a holding member 20 shown in Figs. 1-3, the appliance shall be used for a cigarette, the holding member 20 is removed from the rubber bulb 10 and is replaced by a holding member generally indicated by 120 in Fig. 4. The end 118 of said holding member 120 fits into the outlet 16 of the rubber bulb 10 shown in Fig. 2 and the open end 122 of said holding member 120 is of such a shape, that it may receive a cigarette.

Furthermore, the tubular holding member 20 or 120 of suitable material, for example a plastic or a metal, may be of different shape or may be rigidly connected with the rubber bulb 10. Moreover, the part 20 or 120 may be integral with the body of the rubber bulb 10, so that, in other words, the outlet of the rubber bulb is shaped for receiving the end of a cigar or cigarette.

The appliance shown in Figs. 1-3 may be used by persons, who are not allowed to put a cigar or cigarette in the mouth for customary smoking by

inhaling and exhaling the fumes of tobacco, in the following manner:

For example, a cigar is inserted into the open end 22 of the holding member 20. The cigar is lighted by holding the flame of a match near to it and by blowing air through the holding member 20 and the cigar 24 by means of an alternating compressing and releasing of the rubber bulb 10 held in the hand. Then, the person using the appliance may keep the cigar burning by compressing and releasing at intervals the rubber bulb 10. Preferably, the appliance is held in such a way, that the user thereof may have the satisfaction of seeing the smoke and smelling the aroma of the cigar. This is a perfect substitute for a person, who was used to smoke cigars for the taste of the aroma thereof. On the other hand, nervous persons, who were used to smoke for nervous reasons will find a perfect substitute for steadyng their nerves by the continuous compressing and releasing of the rubber bulb. Moreover, the use of the appliance according to the invention prevents an inadvertent placing of the roll of tobacco, i. e. a cigar or a cigarette, into the mouth.

I have described preferred embodiments of my invention, but it is understood that this disclosure is for the purpose of illustration, and that various emissions or changes in shape, proportion, and arrangements of parts, as well as the substitution of equivalent elements for those herein shown and described may be made without departing from the spirit and scope of the invention as set forth in the appended claim.

What I claim is:

A smoker's appliance comprising a smokable article holder having an enlarged portion for receiving a smokable article and a narrow supporting portion, and a pump comprising a hollow bulb of elastic material having an inlet valve in the wall thereof and an outlet opening only at an end thereof spaced from said inlet valve, said outlet opening constituting a holding means for the narrow portion of the holder and a continuous communication means between that portion of the holder and the interior of the bulb whereby flexing and unflexing of the bulb will permit only the entry of air at the inlet valve and permit air and an air and smoke mixture to pass through the outlet opening and the holder.

JULIUS SCHUELEIN.
